United States Patent Office

Des. 193,758
Patented Oct. 9, 1962

193,758

SIGN

William E. Blommel, Jr., Dayton, Ohio, assignor to The Blommel Sign Co., Dayton, Ohio, a corporation of Ohio

Filed Dec. 1, 1961, Ser. No. 67,774

Term of patent 14 years

(Cl. D1—12)

FIG-1

FIGURE 3 is an end elevational view, the other ends being the same as the end shown.

I claim:

The ornamental design for a sign, substantially as shown and described.
